BERRY PICKER

Filed April 17, 1922

Inventor
Richard C. Trayhorn,

By
Watson E. Coleman
Attorney

UNITED STATES PATENT OFFICE.

RICHARD C. TRAYHORN, OF BINGHAMTON, NEW YORK.

BERRY PICKER.

Application filed April 17, 1922. Serial No. 553,562.

To all whom it may concern:

Be it known that I, RICHARD C. TRAYHORN, a citizen of the United States, residing at Binghamton, in the county of Broome and State of New York, have invented certain new and useful Improvements in Berry Pickers, of which the following is a specification, reference being had to the accompanying drawings.

10 This invention relates to certain improvements in berry pickers and it is an object of the invention to provide a novel and improved device of this general character which can be operated with convenience and 15 facility in picking and collecting berries.

Another object of the invention is to provide a novel and improved device of this general character comprising a container having an inwardly opening closure member together with means for collecting the berries or the like after being picked so that the same may be caused readily to be received within the container.

Another object of the invention is to provide a novel and improved device of this general character comprising a container together with means associated therewith to sever the berries or the like to be picked.

The invention consists in the details of 30 construction and in the combination and arrangement of the several parts of my improved berry picker whereby certain important advantages are attained and the device rendered simpler, less expensive and 35 otherwise more convenient and advantageous for use, as will be hereinafter more fully set forth.

The novel features of my invention will hereinafter be definitely claimed.

40 In order that my invention may be the better understood, I will now proceed to describe the same with reference to the accompanying drawings, wherein:

Figure 1 is a view in perspective of a berry picker constructed in accordance with an embodiment of my invention.

Figure 2 is a longitudinal sectional view taken through the device as herein disclosed with certain of the parts in elevation.

50 Figure 3 is a view in top plan of a second chute especially adapted for use in the gathering of berries in clusters, and

Figure 4 is the rake attachment adapted for use in connection with the chute illustrated in Figure 3.

As disclosed in the accompanying draw-

ings C denotes an elongated container of requisite dimensions and tapered from one end toward the other, the larger end preferably constituting the bottom of the container. The bottom 1 is removably engaged with the container and preferably through the medium of the outstanding pins 2 carried by the bottom 1 and the bayonet slot 3 provided in a wall of the container for 65 co-action with each of the pins 2.

The opposite or smaller end of the container C also has removably engaged therewith a closure member 4. This member 4 is provided with an opening 5^a normally 70 closed by the hinged door or flap 5. This door or flap 5 opens inwardly of the container by gravity and is held against movement upwardly of the container through the medium of the inwardly directed lugs or 75 steps 6 which contact with the outer face of said door or flap 5.

A denotes a chute of desired dimensions and having one end portion annular as at 7 and to telescopically receive the smaller 80 end of the container C, said chute being applied after the closure member 4 has been applied, said chute being held in working position by each of the pins 2' being disposed through a bayonet slot 3' in the annular portion of the chute A.

The forward portion of the bottom 8 of the chute A has secured thereto a toothed blade 9 with which co-acts the blade 10 carried by the outer end portion of the 90 elongated resilient arm 11. The opposite end portion of the arm 11 is anchored or secured as at 12 to the outstanding handle or hand grasp 14 carried by the container C and in order that said arm 11 may have 95 movement in substantially a fixed path of travel said arm is freely disposed through an outstanding guide loop 15 carried by the forward or smaller end portion of the container C. The arm 11 at a point overlying the handle or hand grasp 14 is provided with a button 17 and upon pressure being imposed upon said button the arm 11 will be moved in a direction toward the container C, resulting in the requisite co-action 100 between the blades 9 and 10 to effect the separation of a berry or the like.

It is to be understood that the blades 9 and 10 are disposed on such angles to facilitate the severing of a berry or the like 110 and it is also to be understood that these blades 9 and 10 are adapted to clip the

stem of the berry or the like so the berry or fruit will drop upon the bottom 8 of the chute A.

After one or more berries have been received within the chute A, the container C is tilted until an upright position whereupon the weight of the flap or door 5 together with the weight of the berries or the like upon said flap or door 5 will cause the door to swing inwardly and the berries to pass within the container. Then the container is moved in a position to effect further picking operations and the flap or door 5 will return to its closed position.

15 The blade 10 is removably connected with the arm 11 so that the same may be replaced when required as by a differently shaped blade or so that there may be substituted a rake like member 18, which device is employed when it is desired to pick elder berries or similar berries growing in clusters. When the device 18 is used a second chute A' is employed which has a wider flaring mouth than the chute A. When the device 25 18 is employed the berries or the like upon proper manipulation of the container C are pulled off of the bush without the necessity of a cutting action.

While I have hereinbefore referred to my invention being employed in connection with berries, I wish it understood that it can be used in connection with certain fruits and the like.

From the foregoing description it is thought to be obvious that a berry picker 35 constructed in accordance with my invention is particularly well adapted for use by reason of the convenience and facility with which it may be assembled and operated, and it will also be obvious that my invention 40 is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

A device of the class described comprising a container provided with an entrance opening, a chute extending outwardly from the container and associated with the entrance opening, an outstanding hand grasp carried by the container, an elongated resilient arm having one end portion anchored to the hand grasp, the opposite end portion of said resilient member overlying the chute, a blade engaged with said second named end portion of the resilient member, 60 and an outstanding guide loop carried by the container through which the resilient member is disposed.

In testimony whereof I hereunto affix my signature.

RICHARD C. TRAYHORN.
